SAFETY VALVE

Gerhard J. Friderich, Louisville, Ky.

Application April 28, 1948, Serial No. 23,741

2 Claims. (Cl. 137—315)

(Granted under the act of March 3, 1883, as
amended April 30, 1928; 370 O. G. 757)

1

The invention described herein, if patented, may be manufactured and used by or for the Government of governmental purposes without the payment to me of any royalty thereon.

This invention relates to safety valves for shutting off the flow of gasoline to a stove or the like when the flame is extinguished and particularly to safety valves of the type which are maintained in open position by a solenoid or electro-magnet associated with a thermocouple.

An object of the invention consists in providing a safety valve in which the valve and power unit are mounted in separate and distinct compartments to preclude possible contamination of the latter.

A further object of the invention resides in the provision of a simplified arrangement of parts to facilitate assembly and disassembly of the device.

A still further object of the invention consists in providing a safety valve in which the spring tension on the valve may be readily adjusted to suit varying conditions.

Another object of the invention consists in the provision of a safety valve of the type described having its parts so arranged that the bearing for the valve may also serve as an adjusting means for the valve spring, thereby contributing to the compactness and simplicity of the device as a whole.

Other objects and advantages of the invention will be apparent from the following description when taken in connection with the accompanying drawings, in which,

Figure 1 is a side elevational view of the novel safety valve and the thermocouple for operating the same;

Figure 2 is a front elevational view of the device;

Figure 3 is a vertical sectional view taken on the line 3—3 of Figure 1; and,

Figure 4 is a sectional view taken on the line 4—4 of Figure 2.

As indicated above, the present safety valve is intended for use in controlling the flow of fuel to burners for stoves and the like in which a thermocouple is mounted adjacent the burner so as to retain the fuel valve open so long as the burner is in operation and to permit it to close the burner if the flame should be extinguished for any reason whatsoever.

In such devices, it is usual to employ an electro-magnet or the like as the power unit which is adapted to be energized by the current generated by the thermocouple and it is, of course, highly essential that the power unit be shielded from contamination by the gasoline or other fuel controlled by the valve. The thermocouple, in the present instance, is indicated generally by the numeral 1 and is connected with the power unit 2 by means of a cable 3 entering the interior of

2

the casing 4 through the spud 5. In the present embodiment of the invention, the power unit 2 is in the form of a solenoid, the plunger of which is mechanically connected to a manually operable rod 6 having its upper end provided with a head 7 located exteriorly of the casing.

The casing 4 is formed of two compartments 8 and 9, the former serving as an enclosure for the valve to be described and the latter adapted to snugly receive the power unit or solenoid 2. This compartment 9 may be formed in a separate unit 10 comprising a secondary casing threadedly connected to an extension 11 of the casing 4, or may be formed as an integral part of the latter. The compartments 8 and 9 are open at their upper ends and are provided with a single hood-type closure 12 which has its major portion spaced above the tops of the compartments to provide for the reception of a mechanical connection between the rod 6 and the control valve for the fuel. Additionally, the closure is provided with an opening 13 axially aligned with the compartment 9 and through which the rod 6 extends for convenience in operation. The lid 12 may be secured in a position by a pair of set screws or the like 12' provided with kerfs permitting them to be operated by a coin, serviceman's dogtag, or the like.

The casing 4 is provided with an outlet 14 adapted to be closed by a vertically reciprocal valve comprising a disc portion 15 on which is formed a cone-shaped extension 16 adapted to set in the upper end of the outlet 14. Communicating with the vertical passage 14 is a horizontal duct 17 adapted to be closed at will by a manually operated valve 18 cooperating with the end of the duct adjacent the passage 14. The opposite end of the duct 17 communicates with a threaded opening 19 to which may be connected a fuel pipe for conveying fuel to the control apparatus. Also communicating with the compartment 8, at one side of the valve 16 is a passage 20 leading to a threaded opening 21 to which a pipe is to be connected for carrying fuel to the burner (not shown).

The valve 15—16 is reciprocally mounted within the compartment 8 and is provided with a valve stem 22 extending upwardly through the opening or bore 23 formed in a plug 24 which is threadedly connected to the upper end of the compartment as indicated by the numeral 25. The wall of the opening 23 serves as a slide bearing for the valve rod 22 and is provided with a pair of diametrically opposed keyways 26 into which extend the ends of a pin 27 mounted in the body of the valve rod 22, thereby splining the valve rod to the plug 24 for a purpose mentioned below. A compression spring 28 encircles the lower portion of the valve rod 22 and has its lower end in engagement with the upper surface of the valve

disc 15 and its upper end in engagement with the lower surface of the plug 24.

Between the compartments 8 and 9 the casing is provided with a fulcrum 29 to which a link 31 is connected by means of a cotter pin or the like 30. One end of this link is pivotally connected to the upper end of the valve rod 22 by a cotter pin 32 and the opposite end thereof is pivotally connected by a cotter pin 33 to a knuckle joint 34 secured adjacent the upper end of the operating rod 6 by means of an additional cotter pin 35.

In order that the valve body 16 may be pressed with sufficient pressure against its seat at all times by means of the spring 28, it is desirable that some means be provided for adjusting the spring and this adjustment may be made through the medium of the threadedly mounted plug hereinabove described. By rotating the plug in the proper direction the same will be caused to move downwardly or upwardly, thereby increasing or decreasing the tension in the spring. The plug 24, due to the fact that it is splined to the valve rod 22, may be rotated, to adjust the spring 28, by means of the link 31. For this purpose, it is only necessary to remove the lid 12 and disconnect the link 31 from its fulcrum 29 and the knuckle joint 34; thereafter the link may serve as a handle in rotating the valve rod 22 about its axis which through the spline connection with the plug 24 will permit the latter to travel downwardly or upwardly, in accordance with the direction of rotation, to increase or decrease the pressure of the spring.

In the operation of the safety valve as disclosed herein, it will be understood of course that the thermocouple is to be mounted adjacent the burner, the flow of fuel to which is to be controlled by the safety valve, and it will be further understood that the manually operated valve 13 is to be opened when the burner is to be placed in operation. To light the burner, it is first necessary to press down upon the head 7 of the rod 6 so as to depress one end of the link 31 adjacent the power unit, thereby raising the valve 16 from its seat and permitting the flow of fuel from the passage 17 and duct 14 to the interior of the valve casing 8 and thence downwardly through the passage 20 to a pipe threaded to the opening 21 for conveying the fuel to the burner. After the burner is lighted the rod 6 is maintained in its lowered position for a short period of time necessary for the thermocouple 1 to generate sufficient current to energize the power unit or solenoid 2 to maintain the valve in its raised position, after which the manual operation of the rod 6 may be discontinued. Should the flame be extinguished accidentally or otherwise, the cooling of the thermocouple 1 will cause the generation of electric current to immediately cease, thus de-energizing the power unit or solenoid 2 and permitting the spring 28 to force the valve 16 upon its seat thereby shutting off further flow of fuel from the opening 21 to the fuel pipe leading from the opening to the burner. Should the operation of the safety valve becomes more or less defective by reason of improper pressure of the compression spring 28 upon the valve disc 18, this defect may be readily overcome by adjusting the vertical position of the plug 24 to increase or decrease pressure upon the spring, through use of the link 31 as a handle in the manner described above.

From the foregoing description and the accompanying drawings, it will be apparent to those skilled in the art that I have devised an exceed-

ingly simple and compact construction of safety valve of the thermocouple type, that the structure is such as to prevent contamination of the power unit by contact with the fuel controlled by the valve; that reliable operation of the valve at all times is insured by the adjustment provided for the valve spring; that adjustment of the spring pressure without the use of tools is conveniently provided for in the splining of the valve rod to the plug or bearing for the rod, and that the device may be readily disassembled, also without the use of tools, by releasing the set screws 12', removing the lid and extracting the cotter pins 30, 32 and 33 from the fulcrum 29 and link 31, and may be assembled just as simply.

In accordance with the patent statutes, I have described what I now consider to be the preferred embodiment of the invention, but since various changes may be made in structural details without departing from the spirit of the invention, it is intended that all such changes be included within the scope of the appended claims.

I claim:

1. In a device of the class described, a compartmental valve casing open at its upper end, a removable cover for the casing, a reciprocable valve and valve stem in one compartment, a centrally bored plug threaded into the upper end of said one compartment and serving as a bearing for the valve stem, a splined connection between the valve stem and plug, a spring interposed between the valve and plug, a power unit in another compartment, a fulcrum positioned between the valve and power unit, a link having one end pivoted to the valve stem, and manually operable fasteners connecting the mid-portion of the link with the fulcrum and the other end of the link with the power unit, whereby the link may serve as a handle to rotate the valve stem and the plug splined thereto when the manually operable fasteners are removed.

2. In a device of the class described, a compartmental valve casing, a reciprocable valve and valve stem in one compartment, a centrally bored plug threaded into the upper end of said compartment and serving as a bearing for the valve stem, a splined connection between the valve stem and plug, a spring interposed between the valve and plug, a power unit in another compartment, a fulcrum positioned between the valve and power unit, a link having one end pivoted to the valve stem, and manually operable fasteners connecting the mid-portion of the link with the fulcrum and the other end of the link with the power unit, whereby the link may serve as a handle to rotate the valve stem and the plug splined thereto when the manually operable fasteners are removed.

GERHARD J. FRIDERICH.
